Attorney.

UNITED STATES PATENT OFFICE.

WILLIAM H. SAWYER, OF PROVIDENCE, RHODE ISLAND.

ELECTRICAL CONNECTING-CORD.

SPECIFICATION forming part of Letters Patent No. 269,328, dated December 19, 1882.

Application filed August 23, 1882. (No model.)

To all whom it may concern:

Be it known that I, WILLIAM H. SAWYER, a citizen of the United States, residing at Providence, in the county of Providence and 5 State of Rhode Island, have invented certain new and useful Improvements in Electrical Connecting-Cords; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to an improvement in that class of electrical conductors known as "tinsel connecting-cords," and used for connecting telephones in circuit, making switch-connections, and for other similar purposes 20 within doors. These connecting-cords have heretofore been composed of a round braid or twist of tinsel threads inclosed in a tubular braid of cotton, woolen, or other non-conducting fibrous material. They have great flexi- 25 bility, for which they are chiefly valued, are non-elastic, and answer very well for conducting high-tension magneto-electric currents, for which purpose they have been mainly employed, but are found to have too great re- 30 sistance for general use in connecting up all kinds of electrical apparatus.

It is the object of my invention to provide a braided connecting-cord which shall have less resistance in proportion to size than those 35 of the old style referred to, and be capable of use in conducting freely all kinds of electrical currents, while also being amply flexible, strong, and non-elastic.

The invention consists in an electrical connecting-cord having a core composed of an assemblage of fine copper or other highly-flexible metallic wires inclosed in a tubular braid of tinsel threads, which braid may or may not be in turn inclosed in a tubular braid of non- 45 conducting fibrous material. The central core of fine wires is the main conductor of the cord, and these wires are bound together by the tubular braid of tinsel threads, which, in addition to their function of binding the wires to- 50 gether, add to the conductivity of the cord. The wires prevent the braid from having the objectionable longitudinal elasticity which it would have if used alone. The outer tubular

braided covering of non-conducting material will protect the tinsel, and also prevent crosses 55 and short-circuiting should a cord come in contact with other conductors or another cord.

It will be understood that by "tinsel thread" is meant a thread of fibrous material wound spirally with a very thin and flexible strip or 60 thread of metal.

In the drawings, Figure 1 is a piece of a connecting-cord constructed according to my invention, without the outer non-conducting braided covering. Fig. 2 is a view of a similar 65 cord provided with an outer non-conducting braided covering. Fig. 3 is a longitudinal central section of the cord shown in Fig. 2.

The letter A indicates the central core, which is an assemblage of any convenient number of 70 naked highly-flexible metallic wires, preferably copper, in contact with each other.

B is the tinsel braid which incloses the core-wires, the tinsel being in contact with adjacent wires; and C is the outer non-conducting 75 braided covering, which, as before intimated, may be omitted, but the use of which is preferable as a protector and insulator.

In use a connecting-cord will usually be provided at each end with a metallic tip, with 80 which both the core of central wires and the tinsel braid will be electrically connected. Such tips may be applied in any well-known or convenient manner, forming no part of my invention.

What I claim is—

1. An electrical connecting-cord having a core composed of an assemblage of fine highly-flexible metallic wires inclosed in a tubular braid of tinsel threads, substantially as de- 90 scribed.

2. An electrical connecting-cord composed of the following parts, namely: a central core consisting of an assemblage of fine highly-flexible metallic wires, a tubular tinsel braid inclosing said core and in contact with adjacent wires thereof, and an outer braided covering of non-conducting fibrous material, all arranged as shown and described.

In testimony whereof I affix my signature in 100 presence of two witnesses.

WILLIAM H. SAWYER.
